UNITED STATES PATENT OFFICE.

CHARLES R. SWIFT, OF MIDDLEBORO, MASSACHUSETTS.

GLIDER.

Application filed August 18, 1924. Serial No. 732,695.

To all whom it may concern:

Be it known that I, CHARLES R. SWIFT, a citizen of the United States of America, and a resident of Middleboro, in the county of 5 Plymouth and State of Massachusetts, have invented certain new and useful Improvements in Gliders, of which the following is a specification.

This invention relates to gliders and has 10 for its object the provision of means for warping the tips of the front or main wings of the device when the rudder thereof is actuated.

The invention further consists in means 15 whereby the wings may be actuated independently of any operation of the rudder.

The invention further consists of means for warping the rear or secondary wings of the glider.

20 The invention further consists in certain novel features of construction and arrangement of parts which will be understood readily by reference to the description of the drawings and to the claims to be hereinafter given.

For the purpose of illustrating the invention, one preferred form thereof is shown in the drawings, this form having been found to give satisfactory and reliable re- 30 sults, although it is to be understood that the various instrumentalities of which the invention consists can be variously arranged and organized, and that the invention is not limited to the precise arrangement and organization of the instrumentalities as herein shown and described, except as required by the scope of the appended 35 claims.

Of the drawings:

40 Figure 1 represents a plan of a glider embodying the principles of the present invention.

Figure 2 represents a side elevation of the same.

45 Figure 3 represents a plan of the controlling mechanism for controlling the action of the rudder and wings, drawn to an enlarged scale.

Figure 4 represents a vertical section of 50 the same.

Figure 5 represents in diagram the flexible connection for controlling the movement of the rudder, and

55 Figure 6 represents in diagram the flexible connections for controlling the warping of the rear ends of the rear wings.

Similar characters indicate like parts of the several figures of the drawing.

In the drawings 10 is a car of any usual construction and provided with a cockpit 60 11 in which is positioned a seat 12 for the operator. Near the front of the car 10 and from the sides thereof extend the main wings 13 which may be braced by ribs in any well known manner.

65 Each side wing 13 has a shaft 14 extending lengthwise thereof and to the outer end of each shaft 14 is secured a plurality of arms 15, these arms 15 also being secured to the tips of the wings 13 so that when a shaft 70 14 is oscillated the tip of its wing will be warped.

75 The inner end of each shaft 14 has secured thereto a gear 17, both gears 17 meshing with the intermediate gears 18 and 19.

80 The gear 18 is loosely mounted upon the control shaft 20 and the hub of the gear 19 is fixedly secured to said shaft 20 and is provided with a clutch part 21 which is adapted to be engaged by the clutch part 22 85 formed upon the drum 23 loosely mounted upon the shaft 20 but slidable thereon to permit the clutch members 21, 22 to be engaged when the operator desires to rotate said drum 23, by means of the control 90 wheel.

95 The clutch members 21, 22 are nominally retained in disengaged position by means of the bifurcated lever 24 which is adapted to be moved by the operator's foot in any well known manner.

The shaft 20 has a control wheel 25 secured thereto by which the said shaft 20 and gears 17, 18, and 19 may be rotated.

On the drum 23 is mounted a flexible 95 member 26 which passes over the pulleys 27, 28 on the car 10 and the pulleys 29 on the rear wings 30 and has its opposite ends secured to opposite sides of the rudder 31 at the rear end of the car 10.

100 The rear wings 30 are secured at their forward ends to the opposite sides of the car 10 while their rear ends are entirely disconnected therefrom.

105 These rear wings 30 are provided with the usual ribs and to one of the rear ribs 32 of each wing 30 is connected a flexible member 33 which extends downwardly to a pulley 34 and then into the car around pulleys 35 to the eyes 36 on the rear of the yoke 37 supporting the gears 17, 18, and 19.

110 The opposite ends of the flexible member

33 are secured to said eyes 30, projecting from the rear of yoke 37. Similar flexible members 33 secured to said eyes 36 extend rearwardly above the rear wings 30 over the pulleys 38 and are secured to the ribs 32.

The yoke 37 has bearings in the car 10 in axial alignment with the shafts 14 and is adapted to be tilted about its axis.

When the yoke 37 is tilted to lower the 10 eyes 36 it is obvious that through the flexible member 34 the rear ends of the wings 30 will be warped upwardly and when the yoke 37 is tilted sufficiently in the opposite direction the rear of the wings 30 will be warped 15 downwardly.

With the parts in the position shown in the drawings the operator by means of the control wheel 25 may actuate the shafts 14 and warp the wings 13 as desired.

20 If it is desired to actuate the rudder 31 and at the same time warp the tips of the wings 13, the clutch members 21 are brought into engagement and then both operations may be performed simultaneously.

25 Moreover both of these operations may be performed and at the same time the rear ends of the secondary wings 30 warped by simply tilting the yoke 37 in either desired direction.

30 If desired the warping of the wings 13 may be accomplished with or without performing either of the other operations.

The construction of the device is such that when the operator desires to turn to the left 35 he simply turns the control wheel 25 to the left and a right turn of said wheel 25 will cause the glider to turn in that direction.

At the same time, the tip ends of the planes or front wings 13 may be warped, 40 the end of the right wing, in a left turn, being warped in such a manner that its forward edge is raised while at the same time the front edge of the left wing will be depressed.

45 This warping of these wings 30 in this manner makes more resistance on the tip of the right wing and less resistance on the tip of the left wing thereby causing the glider to bank in making a turn and thus preventing any side slip thereof.

50 The yoke 37 is so hung that by raising the control wheel 25 both shafts 14 will be turned forward warping the tips of both

wings downwardly at their front edges and reducing the resistance on both wing ends.

At the same time through the flexible connections 33 the rear ends of the rear wings 30 will be depressed thereby causing more resistance and pointing the nose of the machine downwardly.

By lowering the control wheel 25 a reverse action would result and the nose of the machine would be raised.

It is obvious therefore that the glider is under absolute control of the operator at all 65 times by the simple manipulation of the control wheel 25 assisted by the movement of the foot when it is desired to bring the rudder control drum 23 into action.

It is believed that the operation and many 70 advantages of the invention will be understood readily without further description.

Having thus described my invention, I claim:

1. The combination of a car provided with 75 a seat for the operator; an oscillating yoke on said car; a rudder on said car; main wings extending laterally from the front end of the car in opposite directions; shafts extending lengthwise of said wings; cross arms secured to the outer ends of said shafts; a shaft revolubly mounted in said yoke; intermediate gears thereon meshing with said wing-shaft gears; a drum on said yoke shaft; and flexible connections between said 85 drum and said rudder.

2. The combination of a car provided with a seat for the operator; an oscillating yoke on said car; a rudder on said car; main wings extending laterally from the front 90 end of car in opposite directions; shafts extending lengthwise of said wings; cross arms secured to the outer ends of said shafts and said wings; gears on the inner ends of said shafts; a shaft revolubly mounted in said yoke; intermediate gears thereon 95 meshing with said wing-shaft gears; a drum on said yoke shaft; flexible connections between said drum and said rudder; and a hand wheel fixedly mounted on said yoke shaft and adapted to be moved into engagement with one of said intermediate gears.

Signed by me at New Bedford, Mass., this 20th day of October 1923.

CHARLES R. SWIFT.
